UNITED STATES PATENT OFFICE.

JOHN C. DUNER, OF CHICAGO, ILLINOIS.

WATER-CLOSET.

Application filed September 26, 1925. Serial No. 58,721.

This invention relates in general to water closet hoppers, and more particularly to such a device especially adapted for use in railway cars, or the like, and has for an object the provision of such a device that will be sanitary and in which the parts may be readily disassembled to permit of thorough cleansing and inspection, or to facilitate the repair or replacement of parts upon occasion.

Another object of my invention resides in providing a quick, detachable connection for holding the bowl and stand in assembled position, which connection is mounted on the exterior of the bowl and stand so as to be readily accessible for assembly and disassembly of the bowl and stand.

Another object of my invention resides in providing the stand with a bracket or other means projecting laterally from the rear thereof to form a mounting for the actuatable flushing mechanism, which bracket or means is formed with a drain connection to the interior of the stand so that water leaking from the flushing mechanism onto the bracket will drain into the stand.

Another important object is to provide such a device having means for preventing liquid from dripping on the floor such as may be caused by leakage of the flushing mechanism, or by the condensation of vapors upon the external surfaces of the flushing mechanism, and to provide a means for the disposal of said liquids.

Numerous other objects and advantages of the invention will be apparent as it is better understood from the following description, which, taken in connection with the accompanying drawings, discloses a preferred embodiment thereof.

Referring to the drawings,

Figure 1 is a perspective view of a device embodying my invention, and showing the parts thereof in disassembled relation;

Fig. 2 is a side elevation showing the device assembled and having a portion thereof broken away to illustrate certain details of construction;

Fig. 3 is a similar view showing a plan view of the device;

Fig. 4 is an enlarged view taken substantially on line 4—4 of Fig. 2 showing certain details of construction;

Fig. 5 is an enlarged view showing a flushing mechanism, and means for mounting said mechanism;

Fig. 6 is a section taken substantially on line 6—6 of Fig. 5, and

Fig. 7 is a section taken substantially on line 7—7 of Fig. 6.

To illustrate my invention, I have shown on the drawings a two part hopper comprising a bowl part 11 and a stand part 12. A plurality of links 13 are preferably provided to secure the bowl 11 and the stand 12 in fixed relation. A bracket 14 is provided, which is or may be secured to the stand 12 and is preferably adapted to support a liquid control mechanism 15. A cover plate 16 may be provided to seal or protect the liquid control mechanism 15.

The bowl 11 is preferably molded of vitreous china or the like and may be of any suitable form having a surface 17, preferably adjacent the top thereof, and adapted to rest upon a wall portion 18 of the stand 12, which may be elliptical, circular or of any other convenient form. Suitable pipe connections or conduit 19 is mounted in the bowl 11 for conducting flushing liquid to the interior thereof, and a pair of vertical bearing brackets 21 are or may be secured to the bowl 11 to facilitate the attachment of suitable seat and cover parts.

The stand 12 may be of any suitable shape having a base 22 adapted to rest upon a floor or like surface and may be of any suitable height, the wall 18 thereof being formed in accordance with the surface 17 of the bowl 11.

A gasket 23 which may be of any soft material, such as lead or the like, is preferably positioned over the top edge of the wall 18 to compensate for possible variation in the top surface of the wall 18. A plurality of laterally disposed notches or recesses or overhanging shoulders 20 may be provided in the stand 12 to facilitate the attachment of the bowl 11. A dump pan 24 of any suitable type and secured to a shaft 25 may be mounted in the stand 12, the shaft 25 having bearings at opposite sides in the stand 12 and being extended beyond said bearings at its ends to receive a weight member 26, which may be secured thereto by any suitable means such as at 27, and an arm 28 for rotating the shaft to dump the pan 24, which is returned to the position shown by the force of gravity through the weight 26.

The links 13 may be of any suitable material and form, and in the present instance, include a portion 31 which may be secured to

the bowl 11 by bolts 32 or the like, a threaded portion 33, a portion 34 having a hooked end 35 for engagement in suitable recesses 20 or the like in the stand 12, a threaded portion 36, and a double threaded nut 37 of the turn-buckle type having suitable apertures 38 providing a means for the operation thereof.

The bracket 14 may be of any suitable material having a portion 41 formed to embrace 10 a portion of the exterior surface of the stand 12 which may be apertured as at 42 to receive bolts or the like by which the bracket may be secured to the stand 12 and a base portion 43 having upwardly extending bearing portions 15 44, 45 and 46, the portion 44 being adapted to provide a means for supporting the liquid control mechanism 15. In the present instance, I have shown the portion 44 terminating at its upper end in a plurality of 20 fingers 47 suitably spaced apart to provide slots 48 adapted to receive bolts or the like for securing the liquid control mechanism 15 in operative position. One of the fingers 47 is preferably extended and tap threaded as 25 at 51 to receive a threaded screw 52.

Any suitable liquid control mechanism may be used, and in the present instance, I have shown such a device of the form and construction shown and described in my 30 earlier Patent 936,706 including a flushing valve 53, an inlet 54, an outlet 55 and a plunger 56. The inlet 54 is connected with a suitable liquid supply source; the outlet 55 is connected to the conduit 19 by a pipe 35 coupling 58 or the like. The conduit 19 is secured to the bowl 11 and communicates with the interior thereof. A bell crank 59 is mounted on the pin 61, which is in turn mounted in the bearing portion 45 of the bracket 14 and a shaft 62 is mounted in the bearing portions 46 of the bracket 14. An arm 63 is secured at one end of the shaft 62 by means of a pin 64. A bracket 65 is secured to the shaft 62 by means of a set screw 66 and 40 is provided with an arm 67 which is preferably connected with a sliding bracket 68 having a portion 69 extending laterally therefrom for engaging the top horizontal surface of the bearing 46 at one end of the shaft 62, and a U shaped portion 71 adapted to embrace a spherical end of an arm 72 of the lever 59. An arm 73 of the lever 59 is adapted to embrace a flanged or enlarged portion 74 on the plunger 56. The base portion 43 of the bracket 14 is preferably formed 45 to provide a shelf or shield beneath the operative parts of the liquid control or flushing mechanism and is preferably depressed as at 75 and at a slight angle to a horizontal plane. A lug 76, which is adapted to extend through 50 an aperture 77, is apertured as at 78. This aperture is preferably below the plane of the depressed portion 75 and communicates therewith for draining liquid from the portion 43 into the interior of the base.

The cover plate 16 which may be of any suitable material is preferably formed to cover the liquid control mechanism and the operating means therefor, has an extended portion 79 adapted to engage in a recess 81 70 in the bowl 11 and to be supported by a bracket 82 secured to the bowl 11 and may be apertured to receive the screw 52 by which it is secured against a horizontal surface 83 on the extended portion 47 of the bearing 75 portion 44.

In operation, the bracket 14 is secured to the stand 12. The liquid control device or flushing valve 53 and the operating linkage therefor is then secured to the bracket. The 80 bowl 11 is then positioned over the stand 12 and secured thereto by means of the links 13. The flushing valve is then coupled to the conduit 19 and the cover plate 16 secured in place. Either part may be separately removed from the base without disturbance of the other after assembly. The operating mechanism for the flushing valve 53 and the dump pan 24 is interconnected by means of a link 91 which is secured to a pin 92 in the 85 arm 28 and by a pin 93 in the arm 63.

It is thought that the invention and many of its attendant advantages will be understood from the foregoing description, and it will be apparent that various changes may 95 be made in the form, construction and arrangement of the parts without departing from the spirit and scope of the invention, or sacrificing all of its material advantages, the form hereinbefore described being merely 100 a preferred embodiment thereof.

I claim:

1. A water closet, comprising, a stand, a bowl attachable to said stand, liquid control mechanism for controlling bowl flushing 105 liquid, a bracket attachable to said stand adapted to provide a support for said liquid control mechanism, and a removable cover plate for protecting said liquid control mechanism and attached to said bracket.

2. A water closet, comprising, a stand, a bowl attachable to said stand, liquid control mechanism for controlling bowl flushing liquid, a bracket attachable to said stand adapted to provide a support for said liquid 115 control mechanism, and a removable cover plate for protecting said liquid control mechanism, said cover plate having interlocking engagement with said bowl and being attached to said bracket.

3. A water closet, comprising a stand provided with opposed recesses formed on the exterior face thereof, each recess providing an overhanging shoulder, a bowl supported by said stand and having a portion projecting thereinto, said bowl having opposed perforations lying in the vertical plane of said shoulders, a threaded bolt in each perforation, a link on said bolt, a nut on said bolt holding said link in position, the lower end 125 130

of said link being threaded, a second link having a hook shaped member engaging in said overhanging shoulder, the upper end of said second link being threaded and a turn-buckle engaging the adjacent threaded ends of the two links.

4. In a water closet, the combination of a receptacle, a bracket mounted on the exterior rear wall of said receptacle, said bracket comprising a plate-like member disposed in a horizontal plane and having upstanding members, flushing mechanism supported by said upstanding members, said plate being constructed and arranged to drain the water 15 escaping from the flushing mechanism directly into the receptacle.

5. In a water closet, the combination of a receptacle, a bracket carried by the rear exterior wall of said receptacle and having a 20 horizontal plate-like portion with upstanding projections, flushing control mechanism mounted in said upstanding projections, the horizontal plate-like portion having a drain pocket therein to receive escaping water from 25 said mechanism, said drain pocket having a tubular forwardly projecting conduit extending through a registering aperture in the wall of said receptacle, whereby to drain said water into said receptacle.

30 6. In a water closet, the combination of a metal stand, a ceramic porcelain bowl arranged within and supported upon said stand, and means connecting said bowl and said stand in fixed relation, said connecting 35 means comprising two elongated and contractible screw connections arranged at opposite outer sides of the stand and bowl, the lower ends of said connections having engagements with the stand and the upper ends 40 of said connections having engagements with the outer sides of the bowl near the upper part of the latter.

7. In a water closet, the combination of a 45 metal stand, a ceramic porcelain bowl arranged within and supported upon said stand, and means connecting said bowl and said stand in fixed relation, said connecting means comprising two elongated and contractible screw connections arranged at opposite outer sides of the stand and bowl, the lower ends of said connections being hooked 50 into shouldered recesses in the outer sides of the stand and the upper ends of said connections having engagements with the outer sides of the bowl near the upper part of the latter.

55 8. In a water closet, the combination of a metal stand, a ceramic porcelain bowl arranged within and supported upon said 60 stand, a flush valve mechanism carried by the stand, a connection between said flush valve mechanism and said bowl and delivering

flushing water within the bowl, and means connecting said bowl and said stand in fixed relation, said connecting means comprising 65 two elongated and adjustable screw connections arranged at opposite outer sides of the stand and bowl, the lower ends of said connections having engagements with the stand and the upper ends of said connections having engagements with the outer sides of the bowl near the upper part of the latter, said connections being inclined oppositely outward from their lower to their upper ends.

9. In a water closet, the combination of a 70 metal stand, a ceramic porcelain bowl arranged within and supported upon said stand, said bowl being formed with an outwardly extending shoulder remote from the bottom edge of the bowl and resting on the 80 top edge of the stand, a flush valve mechanism carried by the stand, a connection between said flush valve mechanism and said bowl and delivering flushing water within the bowl, and means connecting said bowl 85 and said stand in fixed relation, said connecting means comprising two elongated and adjustable screw connections arranged at opposite outer sides of the stand and bowl, the lower ends of said connections having engagements with the stand and the upper ends 90 of said connections having engagements with the bowl at points above said outwardly extending shoulder.

10. A water closet, comprising a metal 95 stand, a ceramic bowl positioned on said stand, holding members on opposite sides of the bowl, each extending horizontally through a wall of the bowl and secured at the inner side of said wall, and securing members engaging said holding members and anchored to said stand for securing the parts together.

11. A water closet, comprising a two part receptacle, means for removably securing the 105 receivable parts in operative relation, flushing mechanism for flushing said receptacle attached to one of said parts, and means attached to the other of said parts for supporting said flushing mechanism and collecting 110 liquid drippings from said flushing mechanism.

12. A water closet, comprising a two part receptacle, means for removably securing said receptacle parts in operative relation, 115 flushing mechanism for flushing said receptacle attachable to one of said parts, means attachable to the other of said parts for supporting said flushing mechanism and collecting liquid drippings from said flushing mechanism, and a detachable cover for covering 120 said flushing mechanism.
